UNITED STATES PATENT OFFICE.

WILLIAM M. SCOTT, OF TREDYFFRIN TOWNSHIP, CHESTER COUNTY, PENNSYLVANIA.

SWITCHING APPARATUS.

1,251,120.

Specification of Letters Patent. Patented Dec. 25, 1917.

Application filed April 8, 1915. Serial No. 20,025.

To all whom it may concern:

Be it known that I, WILLIAM M. SCOTT, a citizen of the United States, residing in Tredyffrin township, in the county of Chester and State of Pennsylvania, have invented a new and useful Switching Apparatus, of which the following is a specification:

My invention relates to electrical control apparatus suitable for switching or controlling heavy electric currents such as used in electric lighting and electric power practice.

My invention resides in a system comprising a plurality of switches or circuit breakers, which may be operated either manually or by power, with suitable means insuring that one of the switches or breakers shall always be in normal, generally open, position and insuring that all of the switches or breakers shall never be simultaneously in abnormal, generally open, position.

In one of its aspects my invention resides in transfer switching mechanism whereby a consumption circuit may be placed at different times in communication with different supply circuits or a supply circuit may be put in communication at different times with different consumption circuits, suitable interlocking means being provided to insure that one of the switches shall always be closed and that all of them shall never be simultaneously closed.

In the preferred embodiment of my invention the switches are operated by a motor, though they may also be operated by hand, with suitable means for positively opening one of the switches when another is closed.

And a further feature of my invention resides in means whereby the closing movement of one of the switches begun by manual effort will be completed by motive power and the positive opening of another switch is insured.

My invention resides in further features of structure and circuit arrangements hereinafter described.

In some of its aspects my invention is similar to that disclosed in Patent No. 993,417, granted May 30, 1911.

For an illustration of one of the forms

my invention may take reference is to be had to the accompanying drawings, in which:

Figure 1 is a side elevational view of the switching mechanism and its operating motor.

Fig. 2 is a side elevational view of a detent or dog, on enlarged scale, forming part of the manual control structure.

Fig. 3 is a fragmentary side elevation illustrating a manually operated lever and the associated switch actuating lever operated thereby.

Fig. 4 is a side elevational view, on larger scale, of one of the members of Fig. 3.

Fig. 5 is a top plan view, partly in section, of a control switch.

Fig. 6 is a side elevational view of the mechanism of Fig. 5.

Fig. 7 is a top plan view of the motor driven mechanism.

Fig. 8 is a side elevational view of the mechanism of Fig. 7, some parts being shown in section.

Fig. 9 is a diagrammatic view illustrating an arrangement of circuits which may be employed.

Referring first to Fig. 9, *a* and *b* indicate the conductors of a consumption circuit which may be placed in communication with the generator or source of energy *G* or other device through the double pole switching mechanism comprising the two switches or breakers *A* and *A'*, or with the storage battery or other source of current *S* or other device through the double pole switching mechanism comprising the two switches or breakers *B* and *B'*.

The apparatus hereinafter described is of such structure that either *A*, *A'* or *B*, *B'* shall always be closed, that both never shall be open simultaneously, and that if one of them should be closed or partially closed, as by hand, closure would be enforced after once instituted, and the other positively opened, and whether operated manually or by motor the closure of one positively opens the other.

Referring now to Figs. 1 to 8, 1 is a base or switchboard, of suitable insulating material, upon which are disposed one vertically above the other the switches or

breakers A and A¹, and beside them, one vertically above the other, the switches or breakers B and B¹.

In Figs. 1 and 9 the switches or breakers A and A¹ are shown in circuit closing position, while breakers B, B¹ are in open circuit position.

The switches or breakers illustrated are of similar structure, indicated by employment of similar reference characters for similar parts, with the exception that the lower breakers A and B are each provided with a manually operable handle or lever hereinafter referred to.

15 For brevity the essential parts of switch A will be pointed out.

Upon the front of the switchboard 1 are secured the main terminal blocks 2 and 3 adapted to be engaged and bridged by the 20 movable laminated contact member 4 carried by the arm 5 pivoted to the housing 6 at 7. Carried by the arm 5 are the usual metallic and carbon shunt contacts 8 and 9 co-operating respectively with the stationary metallic and carbon shunt contacts 10 and 11.

Pivoted to the arm 5 at 12 is the short toggle link 13 pivoted at 14 to the link 15 pivoted at 16 to the link or lever 17 pivoted 30 to the housing 6 at 18. The link 19 is pivoted to the housing 6 at 20 and at pivot 14. This is suitable mechanism for operating the contact member 4 and is merely an example of many structures which may be 35 employed.

In the lower breakers A and B the lever 17 is provided with a notch 21 in which is adapted to engage the dog or detent 22 pivoted at 23 to the manually operable lever 10 or handle 24 which is pivoted at 18 to the housing 6 and has the projection 24^a adapted to engage the spring buffer 25 on the under side of the housing 6.

In the circuit closing position, which is 45 the normal position for the example illustrated, the toggle comprising links 15 and 17 is overtraveled, that is, the center of pivot 16 is slightly to the right of the imaginary straight line joining the centers of 50 pivots 14 and 18, a suitable stop 17^a being provided on the link 17 to prevent overtravel beyond the position indicated. The fact that the toggle is overtraveled restrains 55 or locks the bridging member 4 in its closed position, and to cause it to move to its open position the pivot 16 must be carried back across dead center to allow the toggle 15, 17 to collapse.

Pivoted at 26 to the levers 17 of the upper 60 and lower switches of a pair is a rod 27, causing these levers 17 to move in definite relation in unison with each other. When the arm 24 is in its lower position, the normal position of the dog 22, under the influence of gravity, is substantially that in-

dicated in Fig. 1. When the switch or breaker is in open position, the lever 17 will be in the raised position indicated by the lever 17 back of the rod 27 in Fig. 1. The operator raises the lever 24 in counterclockwise direction about its pivot 18 until the detent 22 drops into the notch 21, whereupon the application of downward pressure upon the lever 24 it will carry lever 17 downwardly in clockwise direction about 75 pivot 18 to expand the toggles and move the bridge 4 to circuit closing position. Near the end of its downward movement the end 24^a of the lever engages the spring 25, compressing the same, and when the operator removes his hand, the spring 25 will return the lever 24 slightly in an upward direction to a distance sufficient to allow detent 22 to drop away from the notch 21 to the position indicated in Fig. 1.

Pivoted at 26 for operating the switches A, A¹ is the connecting rod 28 pivoted at 29 to the crank 30 secured to the lower gear wheel 31 rotatable upon the shaft 32 carried by the lower housing 33. A connecting rod 34 similar to 28 is pivoted at 26 to the lever 17 of the switch B and at its lower end at 35 to the crank 36 secured to the gear 37 which is rotatable upon the shaft 32 but is not positively connected to the gear 31 except under certain hereinafter specified conditions.

Secured to the gear 31 is the beveled gear 38, and similarly secured to gear 37 is the beveled gear 39, the beveled gear 40 meshing 100 with both beveled gears 38 and 39. The gear 40 is an idler rotatable upon the end of the arm 41 which partakes of pivotal or rocking movement upon the shaft 32, the arm 41 carrying at its left end, Fig. 8, a 105 spring 42, the left end of the arm 41 having free movement between the stops 43 and 44 carried by the housing 33.

Disposed beneath the housing 33 is the electric motor M whose armature shaft is 110 vertical and carries at its upper end the gear 45 continuously meshing with the driven gears 46 and 47 driving respectively the worms 48 and 49 connected to the gears 46 and 47 by universal joint couplings. The 115 worms 48 and 49 are adapted to mesh with and drive respectively the gears 31 and 37.

The upper ends of the shafts of worms 48 and 49 are pivoted at 50 and 51 with the toggle links 52 and 53, respectively, which 120 are in turn pivoted at 54 and 55 to the toggle links 56 and 57 pivoted at 58 and 59 to the housing 33. The links 56 and 57 have the slots 60 and 61 in which are disposed the pins 62 and 63 carried on the upper ends of 125 64 and 65 attached to the cores 66 of solenoids 67 and 68. The solenoid 67 controls the worm 48 which meshes with the gear 31, and solenoid 68 controls the worm 49 which meshes with the gear 37. Pivoted 130

at 69 is the bar or beam 70 adapted at its ends to engage or be engaged by the upper ends of the shafts of the worms 48 and 49. Its purpose is to positively hold one worm, 5 as 48, out of mesh with its gear 31 as the other worm 49 is forced into mesh with its gear 37. A certain amount of lost motion is allowed between the ends of the beam 70 and the ends of the worm shafts.

10 Movable with the gear 31 is the arm 71 to which is pivoted at 72 the rod 73 pivoted at 74 to the lever 75 which controls the switch blade 76 which is adapted to engage the stationary contact 77, the members 76 and 15 77 constituting the switch in the circuit of the motor M, the switch being opened, as shown in Fig. 1, when the gear 31 has moved the switches A, A¹ to circuit closing position and closed by the opening movement of the 20 switches, A, A¹. Pivoted to the upper end of the shaft of the worm 48 at 78 is the lever 79 pivoted at 80 to the lever 81 which is pivoted at 82 and carries the contact arm 83 adapted to engage the stationary contacts 84 or 85. This is a localizing switch for robbing the operator's switch of control of the motor M, as hereinafter described. With the switches A and A¹ in circuit closing position, as indicated in Fig. 1, the movable 25 contact 83 is in engagement with contact 84. But when the solenoid 67 is energized to thereby extend the toggle 52, 56 the upper end of the shaft of worm 48 will be moved to the right carrying the contact 83 into engagement with 85.

30 The switches whose movable contact members are 76 and 83, as described, are associated with the driving mechanism for the switches A and A¹. Similar switches are associated with the driving mechanism of the switches B and B¹ and are indicated in Fig. 9 as follows:

35 The movable contact 86 of the motor switch coöperates with the stationary contact 87; and the movable contact lever 88 of the localizing switch coöperates with the stationary contacts 89 and 90.

40 On the base or switchboard 1, in association with both pairs of main switches is the 50 switch illustrated in Figs. 5 and 6, indicated as to its position in Fig. 1. This switch comprises the movable contact member 91 secured to the bar 92 and pivoted at 93 to the bracket 94 which also forms electrical 55 communication with the member 91. On opposite sides of the pivot 93 are disposed the stationary contacts 95 and 96. To each end of the bar 92 there is pivoted at 97 a plunger 98 movable in the tube 99 in which 60 is disposed a spring 100 in front of which are disposed the plungers 101 and 102 disposed respectively in the path of the movable contacts 4 of the lower switches A and B. To a projection 103 on the bar 92 is attached one end of the spring 104, under ten-

sion, whose other end is attached to the post 105.

75 Referring again to Fig. 9, the motor M is shown to comprise the armature 106 and the field winding 107. One terminal of the armature 106 is connected with the conductor 108 which with the conductor 109 form a control supply circuit from any suitable source of energy. The conductor 109 communicates by conductor 110 with the movable contact 111 of the operator's control switch C which is adapted to engage either of the switch contacts 112 and 113. Between the contacts 112 and 113 and the conductor 110 are connected the indicating lamps 114 and 115 and the resistances 116 and 117. The contact 112 is connected by conductor 118 with contacts 84 and 96; and contact 113 connects through conductor 119 with contacts 89 and 95. The contacts 85, 90 and 94 are connected with the conductor 109 by conductor 120. One terminal of the motor field 107 connects by conductor 121 with the contacts 77 and 87, and the movable contacts 76 and 86 connect through the solenoids 67 and 68 with the movable contacts 83 and 88 respectively.

80 The operation is as follows:

85 With the switches A, A¹ in circuit closing position as indicated in Figs. 1 and 9 the generator G is in communication through these switches with the circuit comprising the conductors a and b, and the battery or source S is disconnected from the conductors a, b because the switches B, B¹ are open.

90 To transfer the conductors a, b from communication with generator G to the battery S the operator actuates the control switch C to bring contact 111 into engagement with contact 113, thereby short circuiting resistance 117 and lamp 115, which latter was glowing because its circuit was closed from conductor 109 to conductor 108 through solenoid 68, switch 86, and the motor M, thus indicating that the switches A, A¹ were closed and B, B¹ were open, with the result that there is an increase in the strength of current flowing through the circuit referred to sufficient to energize the solenoid 68 and the motor M. The motor 110 accordingly starts and rotates both worms 48 and 49 and the solenoid 68 attracts its core 66 upwardly, expanding the toggle 52, 57, thrusting the worm 49 into mesh with gear 37, causing the motor to drive the gear 37. In so actuating the worm 49 the localizing switch member 88 is brought into engagement with contact 90 whereby the motor circuit is further closed through conductor 120, contact 90, switch 88, solenoid 68 and the motor M, whereby the motor continues to rotate even if the operator releases the switch C, which returns to central or normal position under the influence of a spring or gravity and separates contacts 111 from 130

contact 113. The rotation of the gear 37 will accordingly pull downwardly on the connecting rod 34 and therefore pull downwardly upon the outer ends of the lever 17 of the switches B, B¹ moving them to circuit closing position where they are restrained by the overtravel of their toggles.

As the gear 37 starts to rotate, at the beginning of the movement above referred to, 10 it drives the idler gear 40 through the gear 39 and the gear 40 being free to tilt upon the shaft 32, rotates in mesh with both gears 39 and 38, the gear 38 remaining stationary until the spring 42 and thereafter the left end 15 of the arm 41 engages stop 43 whereupon the gear 40, being incapable of further tilting, forces the gear 38 to rotate and in turn drives the gear 31, which is free from the worm 48; and the now driven gear 31 raises 20 the connecting rod 28, causing the levers 17 of switches A, A¹ to rotate in counterclockwise direction about their pivots 18, as viewed in Fig. 1, carrying the toggles 15, 17 backwardly across their dead centers to 25 remove the contact members 4 of these switches from their terminal blocks 2 and 3, with the result that the closure of switches B, B¹ is accompanied by a positively forced opening of the switches A, A¹, thus disconnecting the generator G from the conductors *a* and *b* and connecting the battery S to the conductors *a*, *b*. Immediately the toggles 15, 17 of switches A, A¹ have been thus forced backwardly across their dead 30 centers, the toggle mechanism collapses and the switches A, A¹ move rapidly toward open circuit position, being aided by the usual springs or gravity, and in so doing raise the rod 28, that is, cause the rod 28 to 35 run ahead of the driving movement imparted thereto through the gear 40, and the gear 40 being now unloaded, it is driven by gear 39 and it accordingly tilts upwardly, as viewed in Fig. 8, carrying its left end 40 downwardly to the stop 44. This return movement of the idler 40 is in effect a lost motion which allows the movable contacts of the switches A, A¹ to rapidly leave their co-operating stationary contacts to a distance which safely opens the circuit. When 45 the switches B, B¹ reach their circuit closing position the motor switch 86 opens and the localizing switch blade 88 separates from contact 90. And the opening of the switches 50 A, A¹, enforced as above described, is accompanied by a counterclockwise movement of the arm 71, Fig. 1, which closes the motor switch 76, 77, but since the solenoid 67 has not be energized, the localizing switch 83, 55 85 remains open.

During closure of the switches B, B¹ the plunger 102 is forced inwardly tilting the contact 91 to position to engage contact 95 and break connection with contact 96.

60 To thereafter open the switches B, B¹ and

close the switches A, A¹ the operator's switch C is moved in opposite direction to bring contact 111 into engagement with contact 112 whereupon the motor M is started through the now closed motor switch 76, 77, 70 and the solenoid 67 is energized, shifting the worm 48 into mesh with gear 31, which latter is now driven by the motor, to extend the toggle 52, 56 which shifts the localizing switch blade 83 into engagement with contact 85, whereupon the motor continues to rotate without further control thereon by the operator's switch C. The result is that the switches A, A¹ are closed and the switches B, B¹ positively opened, through 80 the agency of the idler gear 40, and the switch arm 91 is returned to the position indicated in Figs. 5 and 9.

The switches may be closed manually by the operating levers 24. To close the 85 switches B, B¹ the lever 24 of the lower breaker B is raised until the dog 22 engages in the notch 21 of the lever 17 of lower breaker B, and upon depressing the handle 24 both breakers B and B¹ are moved to 90 circuit closing position due to the interconnection of the levers 17, by the rod 27. The downward movement of the rod 27 of breakers B, B¹ is accompanied by a downward 95 movement of the rod 34 which therefore rotates the gear 37 and its attached gear 39, which latter operates upon the idler gear 40, as described in connection with the motor closing, which causes an opening of the breakers A, A¹.

At or soon after the inception of the closing movement by manual means, the plunger 102 is thrust inwardly, thereby tilting the contact lever 91 into engagement with contact 95. This results in current flowing from conductor 109 through conductor 120, bracket 94, switch contact 91, contact 95, thence through contact 89, solenoid 68, motor switch 86, and the motor M to conductor 108 with the result that the motor is 110 started as if the control switch C had been shifted to bring contact 111 into engagement with contact 113. In other words, upon starting to manually close the switches the switch 91, 95 is closed and starts the motor 115 which then continues the closing movement even if the operator should relinquish the handle 24. And pursuant to such closure of switches B, B¹ the switches A, A¹ are 120 forcibly opened as previously described.

And in manually closing the switches A, A¹, the motor switch 76, 77 being closed, the switch lever 91 will be tilted back into position indicated in Fig. 9, whereupon the motor M will again be connected through 125 switch 91, 96, contact 94, switch blade 83, solenoid 67, motor switch 76, and the motor M and the closing movement will be carried to completion regardless of the operator.

Both in the motor operation of the 130

switches and the manual operation of them the switch blades 83, 88 engage their contacts 85 and 90, respectively, before they leave their respective contacts 84 and 89.

5 It will be understood that the spring 104 may be omitted. It is employed merely to assure a predetermined position of the switch 91, 96 indicated in Fig. 9 when the system is first put into operation to assure 10 that the desired one of the devices G or S shall first be in communication with the conductors *a*, *b*.

With the parts in the position indicated in Fig. 9, there is a closed circuit through 15 the lamp 115 which accordingly glows and serves to indicate that the switches B, B¹ are open or that the switches A, A¹ are closed. When the switches A, A¹ are open the motor switch 76, 77 is closed, for reasons 20 hereinbefore given, in which case there is a circuit through lamp 114 which glows and serves to indicate that switches A, A¹ are open and that switches B, B¹ are closed. The current passing through these lamps 25 passes in each instance through the motor M and the solenoid 67 or solenoid 68. But this current is too small to energize the solenoid or the motor.

What I claim is:

30 1. The combination with a plurality of switches, of means for locking each of said switches in closed position, means for preventing their simultaneous closure comprising an operating member for each switch, 35 and a connection between said operating members operated by one of said operating members when closing its switch to unlock and positively operate the operating member of another switch to positively open the 40 same, an electro-motive device for actuating said operating members, and means preventing simultaneous actuation of said operating members in the same direction by said electro-motive-device.

45 2. The combination with a plurality of switches, of means for locking each of said switches in closed position, means for preventing their simultaneous closure comprising an operating member for each switch, 50 and a connection between said operating members operated by one of said operating members when closing its switch to unlock and positively operate the operating member of another switch to positively open the 55 same, an operating lever for each of said operating members, and a connection whereby said operating lever actuates its operating member in one direction only.

60 3. The combination with a plurality of switches, of means for locking each of said switches in closed position, means for preventing their simultaneous closure and insuring the closure of one of them comprising an operating member positively connected 65 with a movable member of each switch for

moving the same in opposite directions, and a connection between said operating members causing one of them to move in one direction to unlock and positively open its switch when another of said operating members moves in opposite direction to close its switch, a motive device, and a disengageable connection between said motive device and each of said operating members.

4 The combination with a plurality of 75 switches, of means for locking each of said switches in closed position, means for preventing their simultaneous closure and insuring the closure of one of them comprising an operating member positively connected 80 with a movable member of each switch for moving the same in opposite directions, and a lost motion connection between said operating members causing one of them to move in one direction to unlock and positively 85 open its switch when another of said operating members moves in opposite direction to close its switch, a motive device for actuating said operating members, and means preventing simultaneously actuation of said 90 operating members in the same direction by said motive device.

5 The combination with a plurality of switches, of means for insuring that some of them shall always be closed and all never 95 simultaneously open comprising an operating member positively connected to a movable member of each switch for actuating the same in opposite directions, means for driving said operating members, a connection 100 between said operating members through which one of said operating members is driven by said driving means in one direction when another is driven in opposite direction by said means, and means preventing 105 simultaneous actuation of said operating members in the same direction by said driving means.

6 The combination with a plurality of 110 switches, of means for insuring that some of them shall always be closed and all never simultaneously open comprising an operating member positively connected to a movable member of each switch for actuating the same in opposite directions, means for 115 driving said operating members, and a lost motion connection between said operating members through which one of said operating members is driven by said driving means in one direction when another is driven in 120 opposite direction by said means, and means preventing simultaneous actuation of said operating members in the same direction by said driving means.

7 The combination with a plurality of 125 switches, of means for insuring that some of them shall always be closed and all never simultaneously open comprising an operating member positively connected to a movable member of each switch for actuating 130

- the same in opposite directions, means for driving said operating members, a disengageable connection between said driving means and each of said operating members, 5 a connection between said operating members for driving one of said operating members in one direction when another is driven in opposite direction by said means, and means preventing simultaneous driving of 10 said operating members by said means.
8. The combination with a plurality of switches, of means for insuring that some of them shall always be closed and all never simultaneously open comprising an operating member positively connected to a movable member of each switch for actuating the same in opposite directions, a motive device, a disengageable connection between 15 said motive device and each of said operating members, means preventing simultaneous engagement of said connections between said motive device and said operating members, whereby said operating members may not be actuated simultaneously in the same 20 direction by said motive device, and an indirect connection between said operating members insuring their simultaneous movement in opposite directions by said motive device when one of said operating members 25 is actuated by said motive device.
9. The combination with a plurality of switches, of means for insuring that some of them shall always be closed and all never simultaneously open comprising an operating member positively connected to a movable member of each switch for actuating the same in opposite directions, a connection between said operating members insuring their simultaneous movement in opposite 30 directions when one of said operating members is actuated, said connection comprising an idler gear, and a gear co-operating with each of said operating members meshing with said idler gear.
- 45 10. The combination with a plurality of switches, of means for insuring that some of them shall always be closed and all never simultaneously open comprising an operating member positively connected to a movable member of each switch for actuating the same in opposite directions, a connection between said operating members insuring their simultaneous movement in opposite directions when one of said operating 50 members is actuated, said connection comprising an idler gear, a gear connected with each of said operating members meshing with said idler gear, a pivoted lever carrying said idler gear, and means limiting the movement of said lever.
- 60 11. The combination with a plurality of switches, of means for insuring that some of them shall always be closed and all never simultaneously open comprising a toggle in each switch, said toggle adapted to over- 65 travel to restrain the same in closed position, an operating member connected to each toggle, and a connection between said operating members insuring actuation of one of them in one direction when another of them is actuated in opposite direction.
12. The combination with a plurality of switches, of means for insuring that some of them shall always be closed and all never simultaneously open comprising a toggle in each switch, said toggle adapted to overtravel to restrain the same in closed position, an operating member connected to each toggle, and a lost motion connection between said operating members insuring actuation of one of them in one direction when another of them is actuated in opposite direction.
13. The combination with a plurality of switches, of means for insuring that some of them shall always be closed and all never simultaneously open comprising a toggle in each switch, said toggle adapted to overtravel to restrain the same in closed position, an operating member connected to each toggle, a connection between said operating members insuring actuation of one of them in one direction when another of them is actuated in opposite direction, means for actuating said operating members, and means preventing their simultaneous actuation in the same direction by said actuating means.
14. The combination with a plurality of switches, of means for insuring that some of them shall always be closed and all never simultaneously open comprising a toggle in each switch, said toggle adapted to overtravel to restrain the same in closed position, an operating member connected to each toggle, a lost motion connection between said operating members insuring actuation of one of them in one direction when another of them is actuated in opposite direction, means for actuating said operating members, and means preventing their simultaneous actuation in the same direction by said actuating means.
15. The combination with a plurality of switches, of means for insuring that some of them shall always be closed and all never simultaneously open comprising an operating member positively connected to a movable member of each switch for actuating the same in opposite directions, a motor, a disengageable mechanical connection comprising driving and driven members intervening between said motor and each of said operating members, and a connection between the driven members of said mechanical connections insuring the movement of one of said operating members in one direction when disengaged from said motor when another is driven by said motor in opposite direction.

16. The combination with a plurality of switches, of means for insuring that some of them shall always be closed and all never simultaneously open comprising an operating member positively connected to a movable member of each switch for actuating the same in opposite directions, a motor, a disengageable mechanical connection comprising driving and driven members intervening between said motors and each of said operating members, a connection between the driven members of said mechanical connections insuring the movement of one of said operating members in one direction when disengaged from said motor when another is driven by said motor in opposite direction, and means preventing simultaneous engagement of the driving with the driven members of said disengageable mechanical connections. 70
- 10 17. The combination with a plurality of switches, of means for insuring that some of them shall always be closed and all never simultaneously open comprising an operating member positively connected to a movable member of each switch for actuating the same in opposite directions, a motor, a disengageable mechanical connection comprising driving and driven members intervening between said motors and each of said operating members, a connection between the driven members of said mechanical connections insuring the movement of one of said operating members in one direction when disengaged from said motor when another is driven by said motor in opposite direction. 75
- 15 18. The combination with a plurality of switches, of means for insuring that some of them shall always be closed and all never simultaneously open comprising an operating member positively connected to a movable member of each switch for actuating the same in opposite directions, a motor, a disengageable mechanical connection comprising driving and driven members intervening between said motors and each of said operating members, a connection between the driven members of said mechanical connections insuring the movement of one of said operating members in one direction when disengaged from said motor when another is driven by said motor in opposite direction, said connection comprising an idler gear, and a gear connected to each of said operating members meshing with said idler gear. 80
- 20 19. The combination with a plurality of switches, of means for insuring that some of them shall always be closed and all never simultaneously open comprising an operating member positively connected to a movable member of each switch for actuating the same in opposite directions, means for driving said operating members, a connection between said operating members for driving one of said operating members in one direction when another is driven in opposite direction by said means, a driving motor, a switch controlling the same, means other than said motor for actuating an operating member, and means for shifting said switch to energize said motor for actuating one of said operating members to complete closure of its switch after its closing movement has been initiated by said means other than said motor. 85
- 25 20. The combination with a plurality of switches, of means for insuring that some of them shall always be closed and all never simultaneously open comprising an operating member positively connected to a movable member of each switch for actuating the same in opposite directions, means for driving said operating members, a connection between said operating members for driving one of said operating members in one direction when another is driven in opposite direction by said means, a driving motor, a switch controlling the same, means other than said motor for actuating an operating member, and means for shifting said switch to energize said motor for actuating one of said operating members to complete closure of its switch after its closing movement has been initiated by said means other than said motor. 90
- 30 21. The combination with a plurality of switches, of means for insuring that some of them shall always be closed and all never simultaneously open comprising an operating member positively connected to a movable member of each switch for actuating the same in opposite directions, means for driving said operating members, a connection between said operating members for driving one of said operating members in one direction when another is driven in opposite direction by said means, a driving motor, a double-throw switch controlling the same, and means for shifting said switch to position to energize said motor when either of two of said operating members is moved in switch closing direction, said motor completing the switch closure. 95
- 35 22. The combination with a plurality of switches, of means for insuring that some of them shall always be closed and all never simultaneously open comprising an operating member positively connected to a movable member of each switch for actuating the same in opposite directions, a motor, a disengageable mechanical connection comprising driving and driven members intervening between said motors and each of said operating members, a connection between the driven members of said mechanical connections insuring the movement of one of 100

- said operating members in one direction when disengaged from said motor when another is driven by said motor in opposite direction, a solenoid for causing engagement 5 of each of said driving with said driven members of said disengageable mechanical connections, a switch controlling said solenoid and said motor, and means for shifting said switch to energize said motor to actuate one of said operating members to complete closure of its switch after the closing movement of its switch has been begun by means other than said motor.
23. The combination with a plurality of 15 switches, of means for insuring that some of them shall always be closed and all never simultaneously open comprising an operating member positively connected to a movable member of each switch for actuating the same in opposite directions, means for driving said operating members, a connection between said operating members for driving one of said operating members in one direction when another is driven in opposite direction by said means, a driving 70 motor, a double-throw switch controlling the same, means for shifting said switch to position to energize said motor when either of two of said operating members is moved in switch closing direction, said motor completing the switch closure, and an operator's switch having contacts connected in parallel with the contacts of said motor controlling switch.
24. The combination with a plurality of 15 switches, of means for insuring that some of them shall always be closed and all never simultaneously open comprising an operating member positively connected to a movable member of each switch for actuating the same in opposite directions, means for driving said operating members, a connection between said operating members, a connection between the driven members of said mechanical connections insuring the movement of one of said operating members in one direction when disengaged from said motor when another is driven by said motor in opposite 25 direction, a solenoid for causing engagement of each of said driving with said driven members of said disengageable mechanical connections, a switch controlling said solenoid and said motor, means for shifting said switch to energize said motor to actuate one of said operating members to complete closure of its switch after the closing movement of its switch has been begun by means other than said motor, and an operator's switch having contacts connected in parallel with the contacts of said motor controlling switch.
25. The combination with a plurality of 40 switches, of means for insuring that some of them shall always be closed and all never simultaneously open comprising an operating member positively connected to a movable member of each switch for actuating the same in opposite directions, means for driving said operating members, a connection between said operating members for driving one of said operating members in one direction when another is driven in opposite direction by said means, a driving 45 motor, a switch controlling the same, means for shifting said switch to energize said motor for actuating one of said operating members to complete closure of its switch after the closing movement of its switch has been begun by means other than said motor, and an operator's switch having contacts connected in parallel with the contacts of said motor controlling switch.
26. The combination with an electric 50 switch, of means for manually actuating the same, a motor for actuating the same, a motor controlling switch, and means for shifting said motor controlling switch in response to movement of said manual actuating means to energize said motor to complete the movement instituted by said manual actuating means.
27. The combination with an electric 55 switch, of means for manually closing the same, a motor for closing said switch, and a motor controlling switch operated in response to movement of said manual actuating means to energize said motor to close said switch.
28. The combination with an electric 60 switch, of an operating member therefor, a manually operated member adapted to engage said member to actuate said switch, a motor for actuating said switch independently of said manual actuating means, a motor controlling switch, and means responsive to movement of said manual actuating means for shifting said motor controlling switch to energize said motor.
29. The combination with an electric 65 switch, of means for manually actuating the same, a motor for actuating the same, a motor controlling switch, means for shifting said motor controlled switch in response to movement of said manual actuating means to energize said motor to complete the movement instituted by said manual actuating means, and an operator's switch connected in parallel with said motor 70 controlling switch.
30. The combination with an electric 75 switch, of means for manually closing the same, a motor for closing said switch, a motor controlling switch operated in response to movement of said manual actuating means to energize said motor to close said switch, and an operator's switch connected in parallel with said motor controlling switch.

65 25. The combination with a plurality of switches, of means for insuring that some

31. The combination with an electric switch, of an operating member therefor, a manually operated member adapted to engage said member to actuate said switch, a 5 motor for actuating said switch independently of said manual actuating means, a motor controlling switch, means responsive to movement of said manual actuating means for shifting said motor controlling 10 switch to energize said motor, and an operator's switch connected in parallel with said motor controlling switch.

32. The combination with an electric switch, of means for manually actuating the 15 same, a motor for actuating the same, a motor controlling switch, means for shifting said motor controlling switch in response to movement of said manual actuating means to energize said motor to complete 20 the movement instituted by said manual actuating means, and a switch breaking the circuit of said motor upon the completion of switch movement by said motor.

33. The combination with an electric 25 switch, of means for manually closing the same, a motor for closing said switch, a motor controlling switch operated in response to movement of said manual actuating means to energize said motor to close 30 said switch, and a switch breaking the circuit of said motor upon the completion of switch movement by said motor.

34. The combination with an electric switch, of an operating member therefor, a 35 manually operated member adapted to engage said member to actuate said switch, a motor for actuating said switch independently of said manual actuating means, a motor controlling switch, means responsive 40 to movement of said manual actuating means for shifting said motor controlling switch to energize said motor, and a switch breaking the circuit of said motor upon the completion of switch movement by said 45 motor.

35. The combination with an electric switch, of means for manually actuating the same, a motor for actuating the same, a motor controlling switch, means for shifting 50 said motor controlling switch in response to movement of said manual actuating means to energize said motor to complete the movement instituted by said manual actuating means, and a second switch actuated 55 when said motor is started for maintaining said motor energized independently of said motor controlling switch.

36. The combination with an electric switch, of means for manually closing the 60 same, a motor for closing said switch, a motor controlling switch operated in response to movement of said manual actuating means to energize said motor to close 65 said switch, and a second switch actuated when said motor is started for maintaining

said motor energized independently of said motor controlling switch.

37. The combination with an electric switch, of an operating member therefor, a manually operated member adapted to engage said member to actuate said switch, a 70 motor for actuating said switch independently of said manual actuating means, a motor controlling switch, means responsive to movement of said manual actuating 75 means for shifting said motor controlling switch to energize said motor, and a second switch actuated when said motor is started for maintaining said motor energized independently of said motor controlling switch. 80

38. The combination with a plurality of switches, of a worm gear positively connected with a movable member of each switch for actuating the same, a motor, a worm for each worm gear driven by said motor, means 85 preventing said worms meshing with their gears simultaneously, and a connection between said worm gears for causing one of them when driven by said motor to drive the other in opposite direction through said connection. 90

39. The combination with a plurality of switches, of a worm gear positively connected with a movable member of each switch for actuating the same, a motor, a worm 95 for each worm gear driven by said motor, means preventing said worms meshing with their gears simultaneously, and a connection between said worm gears for causing one of them when driven by said motor to drive the 100 other in opposite direction through said connection, said worm gear driven by said motor operating to close one of said switches and said other worm gear driven through said connection operating to positively open 105 another of said switches.

40. The combination with a plurality of switches, of a worm gear positively connected with a movable member of each switch for actuating the same, a motor, a 110 worm for each worm gear driven by said motor, means preventing said worms meshing with their gears simultaneously, and a lost motion connection between said worm gears for causing one of them when driven 115 by said motor to drive the other in opposite direction through said connection.

41. The combination with a plurality of switches, of a worm gear positively connected with a movable member of each 120 switch for actuating the same, a motor, a worm for each worm gear driven by said motor, means preventing said worms meshing with their gears simultaneously, and a lost motion connection between said worm 125 gears for causing one of them when driven by said motor to drive the other in opposite direction through said connection, said one worm gear driven by said motor operating to close one of said switches and said other 130

worm gear driven through said connection operating to positively open another of said switches.

42. The combination with a plurality of switches, of a worm gear positively connected with a movable member of each switch for actuating the same, a motor, a worm for each worm gear driven by said motor, means preventing said worms meshing with their gears simultaneously, and an idler gear forming a connection between said worm gears for causing one of them when driven by said motor to drive the other in opposite direction through said idler gear.

43. The combination with a plurality of switches, of a worm gear positively connected with a movable member of each switch for actuating the same, a motor, a worm for each worm gear driven by said motor, means preventing said worms meshing with their gears simultaneously, and an idler gear forming a connection between said worm gears for causing one of them when driven by said motor to drive the other in opposite direction through said idler gear, said worm gear driven by said motor operating to close one of said switches and said other worm gear driven through said idler gear operating to positively open another of said switches.

44. The combination with a plurality of switches, of a worm gear positively connected with a movable member of each switch for actuating the same in opposite directions, a motor, a worm for each worm gear driven by said motor, means preventing said worms meshing with their gears simultaneously, a connection between said worm gears for causing one of them when driven by said motor to drive the other through said connection, said connection comprising an idler gear meshing with gears attached to said worm gears, a pivoted lever carrying said idler gear, and means limiting the movement of said lever.

45. The combination with a plurality of switches, of a worm gear positively connected with a movable member of each switch for actuating the same in opposite directions, a motor, a worm for each worm gear driven by said motor, means preventing said worms meshing with their gears simultaneously, a connection between said worm gears for causing one of them when driven by said motor to drive the other through said connection, said worm gear driven by said motor operating to close one of said switches and said other worm gear driven through said connection operating to positively open another of said switches, said connection comprising an idler gear meshing with gears attached to said worm gears, a pivoted lever carrying said idler gear, and means limiting the movement of said lever.

46. The combination with an electric

switch, of a manually operated member, a connection between said member and the movable member of said switch capable of actuating the latter in one direction only, a motor for closing said switch, and a motor controlling switch operated in response to movement of said manually operated member to energize said motor to close said switch independently of said manually operated member.

47. The combination with an electric switch having a movable contact member, of a manually operated member having a disengageable connection with said movable contact member for actuating the same in one direction only, a motor for actuating said movable contact member, and a motor controlling switch actuated in response to movement of said movable contact member by said manually operated member for energizing said motor to continue movement of said contact member independently of said manually operated member.

48. The combination with an electric switch having a movable contact member, of a manually operated member having a disengageable connection with said contact member for actuating the same in one direction only, a motor for actuating said contact member in the same direction, and a motor controlling switch actuated in response to movement of said contact member instituted by said manually operated member for energizing said motor to continue actuation of said contact member independently of said manually operated member.

49. In switching mechanism, the combination with a movable contact member, of a pivoted member for actuating the same, a pivoted operating lever, a dog pivoted on said lever for engaging said pivoted member to actuate the same in one direction only, and means for freeing said pivoted member from said dog after predetermined movement of said contact member.

50. In switching mechanism, the combination with a movable contact member, of a pivoted member for actuating the same, a pivoted operating lever, a dog pivoted on said lever for engaging said pivoted member to actuate the same in one direction only, and a spring compressed by said lever in actuating said pivoted member, said spring returning said lever when released to allow said dog to move to position to disengage from said pivoted member.

51. In switching mechanism, the combination with a movable contact member, of a pivoted member for actuating the same, a pivoted operating lever movable independently of said pivoted member, and a disengageable connection between said pivoted member and pivoted lever comprising means carried by said lever and adapted to engage and actuate said pivoted member in one di-

rection, and means moving said pivoted lever in opposite direction after completion of movement of said pivoted member by said pivoted lever to disengage said means carried by said pivoted lever from said pivoted member.

52. The combination with a switch, of a motor for actuating the same, a disengageable mechanical connection between said 10 motor and said switch, said disengageable mechanical connection comprising driving and driven members, a manually operable member, a disengageable connection between said manually operable member and said 15 driven member, and means for automatically disengaging said manually operable member from said driven member.

53. The combination with a movable con-

tact member of a switch, of a manually operable member for actuating the same, a 20 motor for actuating said contact member, a motor controlling switch actuated in response to movement of said contact member by said manually operable member to energize said motor to actuate said contact member independently of said manually operable member, a disengageable connection between said manually operable member and said 25 contact member, and means for automatically disengaging said manually operable 30 member from said contact member.

In testimony whereof I have hereunto affixed my signature this 6th day of April, 1915.

WILLIAM M. SCOTT.
